S. ENGLISH.

TRACK TERMINAL,

APPLICATION FILED DEC. 21, 1921.

1,407,396.

Patented Feb. 21, 1922.

INVENTOR

UNITED STATES PATENT OFFICE.

SAMUEL ENGLISH, OF PITTSBURGH, PENNSYLVANIA.

TRACK TERMINAL.

1,407,396.

Specification of Letters Patent. Patented Feb. 21, 1922.

Application filed December 21, 1921. Serial No. 523,867.

To all whom it may concern:

Be it known that I, SAMUEL ENGLISH, a citizen of the United States, residing at Pittsburgh, in the county of Allegheny and State of Pennsylvania, have invented a new and useful Improvement in Track Terminals, of which the following is a full, clear, and exact description, reference being had to the accompanying drawings, forming part of this specification.

My invention relates to track terminals, particularly to that type which moves with the car during the stopping period and is moved forward as the car is pulled off of the terminal.

My terminal is provided with two shoes resting on the rail, and the shoes are connected so that they move together longitudinally of the rail, but the connection is such that the pressure produced on one shoe by the weight of the car on that shoe is not transmitted to the other shoe sufficiently to materially increase the friction between that shoe and the rail. By reason of this arrangement, the shoe upon which the weight of the car rests during the stopping period may have a high friction on the rail, whereas the shoe upon which the weight of the car rests when the car is being pulled off the terminal may have a relatively low friction on the rail.

By the foregoing arrangement, a high friction is secured when it is needed to stop the car and a relatively low friction is present as the car is being pulled off of the terminal.

My invention will be better understood by referring to the accompanying drawings exemplifying a device embodying my invention, and in which:

Figure 1 is a perspective view of a track with the device applied thereto;

Figure 2 is a section on the line II-II of Figure 1;

Figure 3 is a section of one of the shoes taken on the center line of the rail;

Figure 4 is a section on the line IV-IV of Figure 1;

Figure 5 is a section on the line V-V of Figure 1, the terminal being shown in dotted lines;

Figure 6 is a side elevation of the shoe for returning the terminal; and

Figure 7 shows, in section, a modification of my invention.

Referring to the drawings, Figure 1 shows a section of a railroad track of ordinary construction and having rails 1 and 2 placed upon ties 3. The rails 1 and 2 are provided with stop plates 4 and 5, respectively. A terminal is shown on each of the rails 1 and 2, but I desire it to be understood that in many instances one terminal will be sufficient. The terminals shown are exact duplicates and a description of one will therefore answer for both.

The terminal, as a whole, comprises two shoes 6 and 7. The shoe 6 will be first engaged by the car, and later the wheel of the car will engage the shoe 7, after having passed over the shoe 6. The shoe 6 is provided with an inclined surface 8, gradually rising from the top of the rail to the point 9. The shoe 6 is provided with a more abrupt incline 10, leading from the point 9 to the top of the rail. The rate of curvature of the incline 10 increases at 11 for a reason which will be apparent later. The shoe 7 gradually increases in thickness from its engagement with the rail to a point 12, whereupon it rises abruptly to the top of the projection 13. The curvature of the part between the points 12 and 13 is made to substantially conform to the circumference of the standard car wheel. The shoe 7 is cut away at 14 for the purpose of decreasing the weight of the shoe. The shoe is provided with a brace 15 for the purpose of strengthening that portion extending between the points 12 and 13. The shoe 6 is provided with a housing projecting downwardly on each side of the rail, the downwardly projecting portions being numbered 16 and 17, as shown in Figure 2. The shoe 7 is provided with a similar housing having portions 18 and 19, extending downwardly therefrom, as shown in Figure 4. The shoes 6 and 7 are connected together by horizontal members 20 and 21. The members 20 and 21 are connected to the shoe 6 by bolts 22 and 23, respectively. The holes 24 in the downwardly extending portions 16 and 17 of the shoes 6 are elongated, as shown in detail in Figure 6. This is to permit a relative vertical movement between the shoe 6 and the members 20 and 21.

The shoe 7 is provided with a wear plate 25, which engages the rail on one side and the shoe 7 on the other side. The wear plate 25 is provided with a rib 26, which fits into 110

a corresponding opening in the shoe 7, as shown in Figure 3. The wear plate 25 is also upturned at 27, so that the upturned portion engages with the end of the shoe 7. By the arrangement shown, the wear plate is moved with the shoe and takes the wear incident to the operation of the device, and at the same time, when the wear plate has been considerably worn down, it 10 may be readily removed from the shoe and a new wear plate substituted therefor.

Stop plates 28 and 29 are fastened to the rails 1 and 2, and the movement of the terminal is limited to the distance between the 15 stop plates 4 and 5 and 28 and 29. The tracks are cut away at 30 and 31 to indicate that the stop plates may be placed at any desired distance apart. Usually one rail length will be a sufficient distance, but 20 this distance may be varied at will.

The joint between abutting rails intermediate the stop plates 4 and 5 and 28 and 29 is of the construction shown in Figures 1 and 5, that is to say, a fish plate 32 is 25 placed around the rail flanges and underneath the same, and is spiked to the ties through openings in the rail flange. The purpose of this arrangement is to permit the downwardly extending portions 16, 17, 18 30 and 19 of the shoes and the members 20 and 21 to freely pass over to the top of the fish plate 32.

By connecting the members 20 and 21 to the shoes 6 and 7, as shown, the accidental 35 or unauthorized willful removal of the terminals from the tracks is prevented.

Figure 7 shows a modified form of my invention. The corresponding parts have the same reference numerals as in the other 40 figures, but have the letter *a* applied thereto.

The only difference between the form of Figure 7 and that shown in the other figures is that the members 20^a and 21^a extend 45 downwardly into contact with the flange of the rail 2^a and thus afford a considerable additional contact and friction surface between the terminal and the rail when the car wheel is on the shoe 7. This arrangement does not substantially increase the friction 50 between the terminal and the rail when the car wheel rests on the shoe 6.

In operation, one or more of the devices is placed at the points shown in Figure 1. When a car to be stopped is run upon the 55 terminal, it first rides up the incline 8 and over the same and on to the shoe 7 and into engagement with the portion between the points 12 and 13. The curvature of this portion is such that the wheel is stopped from 60 rotating and the momentum of the car causes the terminal to slide to the right. The friction between the wear plate of the shoe 7 and the rail is such that the car is stopped by the friction or is slowed down 65 thereby to such an extent that it will be

stopped when the downwardly extending flange portions 18 and 19 strike the plates 4 and 5. After the car is stopped, it will run down the incline face of the shoe 7 and rest on the rail between the shoes 6 and 7. 70 When it is desired to remove the car from the terminal, it is pulled to the left and the wheel rides up the incline 10 until it engages with the steeper portion 11 of the shoe 6, at which time the shoe 6, together 75 with the shoe 7, is moved along the rail until the flange portions 16 and 17 engage the stop plates 28 and 29, whereupon the shoes will be stopped and the car wheel will ride over the point 9 of the shoe 6 and 80 down the incline 8 onto the rail.

By making the wear plate 25 of suitable material, usually soft steel, the friction between the rail and the wear plate is made high when the car wheel is resting on the 85 shoe 7. This provides a high friction during the stopping period of the car. By making the material of the shoe 6 of hard steel or other similar material, the friction between the shoe and the rail will be low, and it 90 will therefore require less effort to return the terminal to its original position and to pull the car off of the terminal than if the friction between the shoe and the rail were higher. Since the shoe 6 performs no function 95 other than returning the device to its initial position, it will be apparent that a low friction is desirable at that time.

My invention has many advantages, among which may be mentioned that high 100 friction is secured during the stopping period and that the wear is taken by a replaceable part which may be easily substituted for the worn part; a shoe of low friction material is used to return the terminal to its initial position, thus reducing the friction between the shoe and the rail; means are used for connecting the two shoes together, so that the friction of each shoe with the rail is localized or limited to the 105 contacting area of that particular shoe with the rail; the device may be easily applied to the rails and removed therefrom, and is simple in construction and automatic in operation. 110

I claim:

1. A track terminal comprising two portions having different amounts of friction when moving on a rail and carrying a part 115 of the weight of a car, and means connecting said portions together to move them longitudinally of the rail while limiting thereto the friction produced between each portion and the track by reason of the weight of the car thereon, substantially as 120 described.

2. A track terminal adapted to be moved upon a track rail, comprising a portion having relatively high friction with the rail 125 to stop a car and a portion having relatively 130

low friction with the rail when the car is being pulled off of said terminal, substantially as described.

3. A track terminal adapted to be moved upon a track rail, comprising a portion having relatively high friction with the rail to stop a car and a portion having relatively low friction with the rail when the car is being pulled off of said terminal, and means 10 limiting the movements of said terminal on the rail, substantially as described.

4. A track terminal adapted to be moved upon a track rail, comprising a portion for carrying a part of the weight of a car during the stopping period of its movement and a portion carrying a part of the weight of a car and acting to return the terminal to its initial position, said portions having different friction with the rail during the 20 movement of the terminal on said rail, substantially as described.

5. A track terminal adapted to be moved upon a track rail, comprising two shoes engaging a rail, means connecting said shoes whereby they may be moved together longitudinally of the rail, said connection permitting independent movement of said shoes 25

whereby the friction between one shoe and the rail produced by the weight of a car thereon is not transmitted to the other shoe 30 in a substantial amount, substantially as described.

6. A track terminal comprising a shoe adapted to carry a part of the weight of a car and to slide on the rail with the car to 35 stop the same, and a second shoe adapted to carry a part of the weight of a car and to slide along the rail to return the device to normal position, said first shoe having a greater friction with the rail than that of 40 the second shoe with the rail, substantially as described.

7. A track terminal comprising a plurality of shoes adapted to be moved along a rail by a car thereon to stop the same, one 45 of said shoes acting to return the terminal to normal position when the car is being pulled off thereof, said shoe having less friction with the rail than that of the first shoe, and means connecting said shoes together, 50 substantially as described.

In testimony whereof I have hereunto set my hand.

SAMUEL ENGLISH.
